UNITED STATES PATENT OFFICE.

SAMUEL F. STEPHENS, OF CHARLOTTE, NORTH CAROLINA.

DESIGN FOR A PIPE-HANGER.

SPECIFICATION forming part of Design No. 33,889, dated January 8, 1901.

Application filed December 1, 1900. Serial No. 33,876. Term of patent 14 years.

To all whom it may concern:

Be it known that I, SAMUEL F. STEPHENS, a citizen of the United States, and a resident of Charlotte, in the county of Mecklenburg and State of North Carolina, have invented and produced a new and original Design for a Pipe-Hanger, of which the following is a specification.

Reference is to be had to the accompanying drawing, forming a part of this specification, in which the figure is an elevation of a pipe-hanger embodying my design.

The design comprises a body part a , which presents a number of concave edges a' , from all of which extend scrolls a'' . These scrolls run into each other in pairs, and from the juncture of each pair passes a single scroll a''' , which scrolls extend upwardly and inwardly toward each other, following the contour of

the members b of the main part of the hanger, which members present the appearance of limbs supporting the lower part of the hanger. Extending upwardly from these limbs b is an elongated member c in the form of a rod, as shown in the drawing.

Having thus described my invention, what I claim as new, and desire to secure by Letters Patent, is—

The design for a pipe-hanger, as herein shown and described.

In testimony whereof I have signed my name to this specification in the presence of two subscribing witnesses.

SAMUEL F. STEPHENS.

Witnesses:

J. L. WATSON,
T. E. KIRKPATRICK.
